UNITED STATES PATENT OFFICE.

JAMES B. ANDERSON, OF SHALER TOWNSHIP, ALLEGHENY COUNTY, PENNSYLVANIA, ASSIGNOR OF ONE-FOURTH TO WILLIAM G. BOYLE, ONE-FOURTH TO JOSEPH GEHRING, AND ONE-FOURTH TO JOHN FUERSTENBERG, ALL OF ALLEGHENY COUNTY, PENNSYLVANIA.

GAS-BURNER.

1,014,111.

Specification of Letters Patent.

Patented Jan. 9, 1912.

Application filed August 16, 1911. Serial No. 644,412.

To all whom it may concern:

Be it known that I, JAMES B. ANDERSON, a citizen of the United States, and residing in the township of Shaler, in the county of 5 Allegheny and State of Pennsylvania, have invented or discovered new and useful Improvements in Gas-Burners, of which the following is a specification.

My invention consists of certain new and 10 useful improvements in burners for either natural or artificial gas or other fluid fuel.

I show novel means for correlating the admission of both air and gas into the mixing chamber so that the proportion of the one 15 element to the other is maintained constant, as regulated, notwithstanding the degree to which the valve mechanism of the burner is opened or closed.

I show a novel multiple needle valve structure which I use in connection with my burner, and means for controlling the same.

I show a plurality of my burners arranged 20 in a battery and connected up for simultaneous and automatic control, so that the 25 temperature predetermined may be maintained without the constant watching of the operator.

Other novel features of construction and arrangement will appear from the following 30 description.

In the accompanying drawings, Figure 1 is a plan view of my burner; Fig. 2 is a longitudinal section thereof along the line II—II in Fig. 1; Fig. 3 is a cross section 35 thereof along the line III—III in Fig. 2, the diaphragm being cut away to show the needle plate and the needle plate being in turn cut away to show the operating lever, and Fig. 4 is a diagrammatic view showing a 40 plurality of my burners, constructed in accordance with the preceding figures, connected together for simultaneous and automatic control, the thumb nuts and the ears being omitted.

The following is a detailed description of 45 the drawings. The burner casing proper is composed of the gas chamber A, the valve box B and the mixer C through which the mixture of gas and air is injected into the 50 furnace, not shown. The gas chamber A has a reduced outer end by which it is connected to the source of gas supply, such as the pipe 1. The ends of the valve box B are threaded externally and engage respectively

the internal threads on the ends of the parts 55 A and C. The mixer C has a cylindrical base, and a tapered outer or discharge end to act as an injector for the mixture.

2 is an internal shoulder in the butt of 60 mixer C adjacent to the threads therein.

3 is a diaphragm plate which fits up 65 against the shoulder 2 and is held in place by the end of valve box B when the latter is screwed into place. The diaphragm 3 is provided with a plurality of perforations 65 4—4 preferably arranged in an annular series concentric with said diaphragm.

5 is a concentric stem and 6 an eccentric 70 stem extending from diaphragm 3 into the interior of element B.

7 is a needle plate, preferably having a solid circular center and arms 8—8 extending radially therefrom, upon which arms are mounted the needles 9—9, preferably tapered, which engage the perforations 4—4 75 in the diaphragm 3. The plate 7 is provided with an axial stem 10 which is provided with a longitudinal perforation to accommodate the stem 5 of the diaphragm 3 and a hole 11 is also provided through the 80 plate 7 engaged by the stem 6 to prevent accidental rotation of the plate 7.

12 is a journal box cast or formed integral with the outer wall of valve box B and communicating therewith by means of a slot 13. 85 But one end of the box 12 is open and the rock shaft 14 extends thereinto, a stuffing box 15 being provided to prevent the escape of gas through the open end of said journal box. An arm 16 is screwed onto the inner 90 end of shaft 14, which is threaded for that purpose, said arm extending through said slot 13 into the interior of valve box B where it engages a lateral recess 17 in the stem 10 of needle plate 7, said recess having 95 its top and bottom walls beveled toward the ends of the recess to permit the arm 16 to rock freely. It is evident that the rocking of the shaft 14 will correspondingly move the plate 7 and the needles 9—9 in the perforations 4—4 thus altering the discharge capacity of said perforations, and regulating the amount of gas admitted to the mixer C.

18 is a lock nut screwed up on shaft 14 105 against the arm 16 to hold it against rotation on the rock shaft.

19—19 represent longitudinal air ports in

the butt of mixer C and 20 is a cylindrical shutter slidingly mounted on the butt of said element to regulate the admission of air through said ports into the interior of 5 mixer C.

21 is a rocking lever pivoted intermediate of its ends to the stud 22 on the mixer C.

23 is a link pivoted at one end to one end 10 of the lever 21 and at its other end to a stud on the shutter 20.

24 is an arm mounted on the exposed end 15 of rock shaft 14 and held against rotation thereon by a set screw 25. 26 is a slot in the other end of arm 24 in which at any desired point may be locked the pin 27 which is 20 pivotally connected to the end of rocking lever 21. It is thus evident that by the above mechanism the movement of the shutter 20 for the admission of air into the mixer C 25 is correlated with the movement of needle plate 7 which controls the admittance of gas into the mixer C, and the proportion of air to gas is maintained constant. The proportion may be adjusted by rotating the 30 arm 24 on the rock shaft 14 and fixing it in its adjusted position by the set screw 25, or by moving the pin 27 along the slot 26 and fixing it in its adjusted position.

To provide a convenient means for operating the mechanism which controls the shutter 20 and the needle plate 7, I prefer to provide the lever 24 with a lateral projection 28 which is pierced by a threaded hole engaged by the threaded end of the thumb bolt 35 29 whose other end is held against longitudinal movement between the ears 30—30 on gas chamber A. It is evident that the rotation of the bolt 29 will raise or lower the lever 24 and therefore will open and 40 close the shutter 20 and adjust the needle plate 7. A set screw 31 may be provided to prevent the accidental rotation of bolt 29 in the projection 28.

As it is frequently desirable to operate a 45 battery of burners in conjunction, I connect the operating mechanism of the same to a rod 32 whose lateral pivot studs 33 engage holes 33^a—33^a in lateral extension 34—34 on the arms 24—24, so that a longitudinal 50 movement of said rod 32 adjusts the shutters 20 and the needle plates 7 of the burners at one and the same time and to the same degree.

To provide automatic control for a 55 battery of burners a device of any convenient type, operated by the temperature of the furnace or boiler may be connected up with rod 32 to actuate the same cutting down the supply of mixed air and gas when the temperature rises beyond a predetermined degree and increasing the same when the temperature falls below said degree fixed upon. Thus in case of a steam boiler or steam boilers, I may provide a steam cylinder 35 connected at its rear end by a pipe 36 with the

boiler. Under the influence of the steam admitted through the pipe 36 the piston 37 in said cylinder is forced forwardly against a coiled spring 38 whose other end bears against a plate 39 in the cylinder 35 and mounted on the end of the stuffing box 40 which is threaded into the front end of the cylinder 35, so that by the movement of said stuffing box the tension of the spring may be adjusted. The piston rod 41 passes 7 through said stuffing box and is coupled up to the rod 32. The spring 38 may be adjusted to any desired resistance, which is overcome when the pressure in the boiler and consequently in the cylinder 35 rises to a 80 fixed degree, thus forcing the piston outwardly against said spring and cutting down the amount of mixed air and gas admitted through the burner or burners connected to rod 32. When the pressure falls, 85 the spring 38 overcomes the pressure in the cylinder and forces the piston rearwardly and restores the normal amount of air and gas admitted to the burners.

Where my burners are connected up with 90 a rod 32 for simultaneous operation, I prefer to unscrew and remove the thumb bolts 29, as shown in Fig. 4.

The thumb bolts 29 and the ears 30—30 are omitted from the burners in Fig. 4 since 95 they are not needed when the burners are automatically controlled.

The advantages of my invention are manifold. Among them may be mentioned the following. Convenient and inexpensive 100 mechanism is provided for correlating the gas and air supplies; so that the flame is maintained at a constant degree of richness which can be changed at any time by means of the adjustments provided to suit different 105 characters of gas, &c. The multiple needle structure enables me to siphon a larger amount of air in to mingle with the gas by the use of a less quantity of gas than would be required in the case of a single needle 110 valve. The gas is also admitted in finer particles over the area of the mixing chamber, enabling me to obtain a more intimate mixture and therefore a more effective and powerful fuel. The pressure of the gas admitted through the plurality of the needle valves is greater than that with which gas from the same supply would enter the mixing chamber through a single needle valve 115 of the combined area of my plurality of 120 valves. The proportion of air to gas can be quickly and accurately adjusted. A battery of my burners can be conveniently operated in unison and may be automatically controlled by the temperature in the furnace or 125 boiler. This automatic control may be applied to a single burner if desired.

What I desire to claim is:—

1. In a gas burner containing a mixing chamber provided with air ports and a gas 130

passage leading into the same, a shutter adapted to close said ports, a multiple needle valve in said passage, a common control for said shutter and said valve, whereby 5 a predetermined ratio may be maintained between the gas and the air, and means for adjusting said control to vary said ratio.

2. In a gas burner, a multiple needle valve consisting of a perforated diaphragm interposed in the gas passage, a plate mounted in said passage to slide longitudinally thereof, needles mounted on said plate and engaging the perforations in said diaphragm, a stem provided with a notch extending 15 axially from said plate, a rock shaft mounted without the gas passage, and an arm fixed to said rock shaft and extending through the wall of said gas passage and engaging the notch in said stem, for the purpose described.

20 3. In a gas burner, a multiple needle valve consisting of a perforated diaphragm interposed in the gas passage, a plate mounted in said passage to slide longitudinally thereof, needles mounted on said plate and engaging the perforations in said diaphragm, a gas tight journal box communicating with 25 said passage, and a rock shaft journaled in said box and operatively connected with said plate, whereby the passage of gas 30 through said perforations may be controlled.

4. In a gas burner containing a valve chamber and a mixing chamber which is provided with air ports through the wall thereof, a perforated diaphragm interposed 35 between said chambers, a needle plate mounted to slide longitudinally in said valve chamber, needles mounted on said plate and engaging the perforations in said diaphragm, a shutter adapted to cover said air ports, 40 and common operative means for moving said needle plate and said shutter in unison, whereby a predetermined ratio between the quantities of gas and air admitted to said mixing chamber is maintained.

45 5. In a gas burner containing a valve

chamber and a mixing chamber which is provided with air ports through the wall thereof, a perforated diaphragm interposed between said chambers, a needle plate mounted to slide longitudinally in said valve chamber, needles mounted on said plate and engaging the perforations in said diaphragm, a gas tight journal box communicating with 50 said valve chamber, a rock shaft mounted in said box, an arm rigidly attached to said shaft and extending into said valve chamber and connected to said needle plate, a shutter controlling said air ports, and operative connection between said rock shaft and 55 said shutter, whereby said needle plate and said shutter are moved in unison and a predetermined ratio is maintained between the 60 quantities of gas and air admitted to said mixing chamber.

6. A plurality of gas burners, each burner 65 containing a valve chamber and a mixing chamber provided with air ports through the wall thereof, a perforated diaphragm interposed between said valve chamber and said mixing chamber, a needle plate mounted 70 to slide longitudinally in said valve chamber, needles mounted on said plate and engaging said perforations, a rock shaft, an arm rigidly mounted on said rock shaft and extending through the wall of said valve 75 chamber and engaging said needle plate, a shutter adapted to close said air ports, operative connection between said rock shaft and said shutter whereby they move in unison, and common controlling means operatively 80 connected with the said operative connection on each burner whereby all of said burners may be operated in unison.

Signed at Pittsburgh, Pa., this 15th day of August, 1911.
